United States Patent Office

Des. 227,285
Patented June 12, 1973

227,285

TOY COASTER WAGON

Leonard Stobar, Granada Hills, Calif., assignor to
Kusan, Inc., Nashville, Tenn.

Filed Mar. 13, 1972, Ser. No. 234,466

Term of patent 14 years

Int. Cl. D21—01

U.S. Cl. D34—15 AJ

FIG1

FIG2

FIG.3

FIG.4

FIG. 1 is a front elevational view of a toy coaster wagon showing my new design, the flagstaff being broken away for ease of illustration;

FIG. 2 is a right side elevational view thereof, the left side being substantially a mirror image thereto;

FIG. 3 is a rear elevational view thereof, the flagstaff being broken away for ease of illustration;

FIG. 4 is a top plan view thereof.

I claim:

The ornamental design for a toy coaster wagon, as shown and described.
